UNITED STATES PATENT OFFICE

124,082

DESIGN FOR A VENETIAN BLIND

Morgan Schrack, Beaverton, Oreg.

Application October 30, 1939, Serial No. 37,948

Term of patent 3½ years

To all whom it may concern:

Be it known that I, Morgan Schrack, a citizen of the United States, residing at Beaverton, in the county of Washington and State of Oregon, have invented a new, original, and ornamental Design for a Venetian Blind, of which the following is a specification, reference being had to the accompanying drawing, forming a part thereof.

The figure is a perspective view of a Venetian blind, showing my new design.

I claim:

The ornamental design for a Venetian blind, as shown.

MORGAN SCHRACK.
